H. THOMAS AND J. DAHLSTROM.
FEED REGULATOR FOR POWDERED COAL.
APPLICATION FILED SEPT. 12, 1919.

1,388,129.

Patented Aug. 16, 1921.

FIG. 1

FIG. 2

INVENTOR

Hansae Thomas
and John Dahlstrom
By Stay Letter Powell

UNITED STATES PATENT OFFICE.

HANSON THOMAS AND JOHN DAHLSTROM, OF PITTSBURGH, PENNSYLVANIA.

FEED-REGULATOR FOR POWDERED COAL.

1,388,129.

Specification of Letters Patent. Patented Aug. 16, 1921.

Application filed September 12, 1919. Serial No. 323,381.

To all whom it may concern:

Be it known that we, HANSON THOMAS and JOHN DAHLSTROM, citizens of the United States, residents of Pittsburgh, in the county 5 of Allegheny and State of Pennsylvania, have invented a new and useful Improvement in Feed-Regulators for Powdered Coal; and we do hereby declare the following to be a full, clear, and exact description 10 thereof.

Our invention relates to a feed regulator for powdered fuel.

In Letters Patent of the United States No. 1,304,407, granted to us on the 20th of 15 May, 1919, we have set forth and claimed a certain improvement in feed regulators for powdered fuel in which a deflecting member is located at the discharge opening of a supply pipe for conveying the air and powdered fuel in the path of said air and fuel, said deflecting member being movable to and from said opening, whereby a portion of the air and fuel in its passage through 20 said supply pipe is discharged through said opening. While the invention of the above patent has many advantages over anything in the prior art, yet it has been found in practice that the powdered fuel collects around the stem of the deflecting member 25 which passes down through the connection leading from the opening in the supply pipe to the pipe leading to the furnace, and clogs up the opening through which said stem passes, whereby it is a difficult matter and 30 sometimes practically impossible to raise and lower the deflecting member. Powdered fuel which is reduced to a very fine state will find its way into and around the closest joints and builds up or cakes at such points 35 which causes the difficulty above referred to.

The object of our present invention is to provide against this sticking of the stem for operating the deflecting member due to its becoming clogged up by the pulverized fuel, 40 and to these ends our invention comprises the novel features hereinafter set forth and claimed.

In the accompanying drawing Figure 1 is a longitudinal section of a portion of a supply pipe for conveying the combined and pulverized fuel, showing our invention applied thereto, and Fig. 2 is a cross section 45 of same.

In the accompanying drawing the number 50 55 2 designates a suitable main supply pipe or branch from the main supply pipe

for conveying the powdered fuel under blast to the furnaces. We have only shown one connection from this pipe to the furnace, although it is apparent that branch pipes 60 are to be attached at different points according to the number of furnaces to be supplied therefrom.

A saddle 3 is secured in position by the U-bolts 4 and nuts 5. Secured to the saddle 65 3 is the elbow-casting 6 with the passage 7 formed therein. This casting 6 has the flange 8 and said casting is secured to the saddle 3 by the threaded bolts 9 screwed into said saddle and provided at their outer ends 70 with the nuts 10. By this construction the casting 6 and the bars carried thereby may be readily detached from the supply pipe for repair purposes.

The neck-portion 11 of the casting 6 projects up into the pipe 2 through the opening 12 formed therein. The saddle 3 has also the neck-portion 13 projecting up into the pipe 2, and the neck 11 of the casting 6 fits within the neck-portion of said saddle. 80

The casting 6 has the opening 14 formed therein to receive the stem 15. The opening 14 is formed in the inclined portion 14^a of the casting 6 so that when the stem 15 is turned in said opening 14 said stem will be 85 wiped for a distance between the points *a* and *b*, due to its passing through the opening 14 formed in the inclined portion 14^a, as will be more fully hereinafter described.

The stem 15 has the threaded portion 16 90 which engages the threaded seat 17 in the bracket 18 of the casting 6. The lower end of the stem 15 is provided with the head 19 with an opening 19^a for the reception of a bar for turning the stem 15. 95

The inner end of the stem 15 carries the deflector or discharge member 20, said member consisting of an inverted cone.

When our improved regulator is in use and the powdered fuel is to be delivered to 100 the furnace through the pipe 26, the deflector 20 projects within the pipe 2 as indicated in Fig. 1, and the combined air and coal traveling in the direction of the arrow will be caught or deflected by the deflector 20 105 and discharged down into the passage 7 and thence by the pipe 26 to the furnace. By turning the stem 15 the position of the deflector may be regulated so as to increase or decrease the amount of fuel delivered to the 110 furnace, it being apparent that by withdrawing the deflector the area exposed to

the oncoming fuel is reduced and consequently the amount of coal delivered to the furnace is reduced. Where it is desired to cut off the supply entirely the stem 15 is turned until the deflector 20 is withdrawn to the position indicated in dotted lines Fig. 1, and is seated on the neck portion 11 of the casting 6. In this position of the deflector the supply of fuel to the pipe 26 is completely shut off. As the deflector is turned when seated it will be apparent that due to the conical form of the deflector the seat as well as the deflector will be wiped clean so as to remove any fuel dust which has 15 collected around the seat.

The turning of the stem 15 working in the opening 14 in the inclined portion 14^a of the casting 6 will act to wipe and clean the stem so as to prevent the sticking of the 20 stem due to the clogging or caking of the pulverized fuel around the stem. This construction always insures the proper movement of the stem, and consequently the accurate adjustment of the deflector 20.

What we claim is:

In a feed regulator for powdered fuel, the combination of a supply pipe for conveying the air and powdered fuel, having a discharge outlet, a connection leading from said outlet having an opening formed therein, with inner and outer inclined faces surrounding said opening, a rotary stem carried by said connection and passing through said opening, and a deflecting member carried by said stem adapted to be projected 35 into the path of the air and powdered fuel, or withdrawn therefrom whereby a portion of the air and powdered fuel in its passage through said pipe is discharged through said discharge opening.

In testimony whereof, we the said HANSON THOMAS and JOHN DAHLSTROM, have hereunto set our hands.

HANSON THOMAS.
JOHN DAHLSTROM.
